James Weston Providence Rhode Island
Sellers Patent

The Schedule refers to in this Sellers Patent and making part of the same,
Containing a description in the words of the said James Weston's Patent
of his Improvement called the Elliptical Spindle Grinder.

(Specification and Description of the Elliptical Spindle Grinder being an Improvement
on the Spindle Grinder in common use, and which may be used for grinding various
things with spindles.)

It is known and remained that James Weston
Mechanic at Providence in the County of Providence and State of Rhode Island
has invented a new and useful Improvement, on the Spindle Grinder called
by me, the Elliptical Spindle Grinder which can be used for grinding other
articles besides spindles the construction operations and advantages of which may
be this specified and detailed to wit.

In the drawing, first named A.A.
represent the frame of the machine B.B.B. the lower a common shape from
which Motion is communicated to the carriage to the article to be ground
C.C.C. and may be slide on the top of the frame, in which the carriage D.D.
moves. The carriage is made of iron or other hard metal and has two
admiral on the railway or slide. The length of the spindle or other thing
to be ground is so great that every part of it in description to the frame
The Motion of the carriage together with the rotary motion of the spindle
a thing to be ground, hereafter mentioned is caused from the frame B.B.B.
by means of both end of slides and cog wheels, within these parts of the
Machine are their relative positions nor their operation being from the
inner part of the machine called the Spindle Grinder than in use
the top of the carriage is the lathe that holds the spindle or thing to
be ground. This is also in the old machine but its made of iron and
with the carriage as shown above. as well as the method of grinding

it will move in the carriage, from the centre of the carriage, or about the centre, lengthwise and now the case of it, next the granular explosive, namely a stick, piece which is fast in the carriage, may easily in a short time, Mr. Sotheby might be enabled easily, round on his nose it out for the part of the machine, it ought to be made to be perfectly timed as it moves in the carriage, and at the same time to give it the same motion forward and back like the carriage seat, In the old machine the back has the same motion forward, and back as the carriage and also a motion from side to side, This same effect may also be produced by connecting the back to the carriage by means of wheels or pulleys made fast to the one and moving, in grooves, made to the other, But this mode of carriage though from a mechanical point to the one first described;

On the top of the side of the frame, does not rotate from the granular explosive, does not rotate from the back, and the back is the back of the latter, ~~is~~ ^{is} the back of the latter, ~~is~~ ^{is} against this back the back paper to its paper back and forward on the carriage, the back or first which forms its connection with the carriage, permitting it always to keep against it, although it is not in a right line with the side of the latter, The same result can be obtained by having the back made to rotate on the other side of the latter, so connecting it, This is also enabled or after the picking of the back against the back and also on the carriage is diminished by the use of friction pulleys, The back is kept steady and its back against the back by means of the friction, which and weight one of which is fastened to each end of the carriage & a stick, The stick being up on a pulley on the back upon which the weight is suspended, one of these is seen in the drawing and is marked D.

On the top of the latter are attached six by a screw bolt, passing through a slot in the spindle, and it made of hard, or other soft metal, The thickness of the slot is equal to the diameter of the thing to be ground, and its length depends upon the length of the thing to be ground, Against the side of this slot holds the granular explosive, the spindle a thing to be ground, prepared, and ready, By means of two jaws

149

passing through a shoulder on the other side of the rest and passing
with him stands passing through it near the other side the hand passing
right in the rest, the rest itself is passed toward the ground to
as it were away by use. The shape size and substance of the rest
are claimed as here.

The Spindle or thing to be ground is held at each
end by a spring contrivance which is known. Motion being communicated
to it by a belt from the Drum D.B.B.

If the Groundstone moves in an inclined carriage on a
frame extending back at right angles from the frame first described
this carriage with the stone in it can be moved in its frame to and
from the spindle or thing to be ground by a lever in front of the first
described frame. The friction force is diminished by the use of wheels or
Ricchin passing under the carriage. The position of the Groundstone and the
carriage to which it is moved with its carriage and frame are the
same as in the old machine. The back of the latter $11\frac{1}{2}$ ft of a description
is made of other board material and its shape is said according
to the shape of the spindle or thing to be ground.

In operating a machine with this
improvement a rest is made corresponding in length and thickness
with the length and diameter of the thing to be ground and is applied
to the back as a rester. A leather back of proper shape is applied
to the rest on this frame. The spindle or thing to be ground is then
fixed on its center in back of the rest passing against it. Motion
being communicated to the drum a piece rotary motion is given
to the spindle or thing to be ground and the leather braces back
and forward on its carriage the force of it being kept against
the leather back by means of the weight of a described rest. The
purpose of the groundstone against the thing which is being ground
Ricchin being at the same time communicated to the Groundstone
and the Groundstone by means of the lever being thrown and held
against the spindle or thing to be ground as it passes the latter
the regressed shape is given to the spindle or thing to be ground.

Means and of preventing from this improvement are that the upon
the a thing ground, with the same back of the latter are injuriously
the peccan skin have the lathered performed with much less
expense than by the ordinary method.

That I claim as my invention the
connection between the latter & carriage by means of the point or stick
plana and move as a screw or screw by which each end of the latter is
able to move to or from the grindstone and the whole latter is
constrained to vibrate the length of the slot in which the stick or point
is inserted -- --

The stick so called which guides the latter
being of such form as to prop the spindle to being to be ground against
the face of the grindstone in such manner as to produce the desired
desired in the thing to be ground and also the use of weights to assist
in keeping the latter against said track and in keeping the latter
steady until the rest aforesaid.

Witness,

Philip D. Martin
William R. Staples
